UNITED STATES PATENT OFFICE.

BERNARD A. GEURINK, OF EAST CLEVELAND, OHIO.

GAS BURNER.

Application filed June 19, 1924. Serial No. 721,003.

This invention relates to a gas burner. More particularly it comprises a gas burner of the type wherein air is mixed with the gas at one end of said burner and the mixture consumed at the other end of said burner, the constructional features of said apparatus insuring the proper proportions of air and gas and rate of flow to the jet end of said burner, and the jet having characteristics insuring perfect combustion.

The principal object of the present invention is to improve the construction of gas burners of the type referred to. Another object of the invention is to provide a novel form of jet or nozzle for a gas burner which will operate in a more efficient manner than those heretofore known. A further object of the invention is the provision of means for adjusting such jet to any desired degree of angularity with respect to the gas passageway. Other objects of the invention will appear in the course of the following description. To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing:—

Fig. 1 is a top plan view of a gas burner embodying the features of the invention; Fig. 2 is a central longitudinal sectional view of the structure shown in Fig. 1, with the nozzle portion of the device shown below the plane of the tube section instead of above said section as in Fig. 1; Fig. 3 is a fragmentary plan view showing the connection of the mixing tube with the nozzle section of the burner; Fig. 4 is a fragmentary sectional view showing the off-set marginal flanges at the meeting edges of the upper and lower sections of the nozzle portion of the burner, said view being taken along the line 4—4 shown in Fig. 3, looking in the direction of the arrows; Fig. 5 is an inside plan view of one of the members of the nozzle portion of the burner, showing the construction and spacing of the lugs at the forward edge thereof; Fig. 6 is a front elevation of the forward edge of the nozzle section of the burner with the preferred form of lugs; and Fig. 7 is a view similar to Fig.

6, showing a somewhat different form of lugs.

As is clearly shown in the drawing, the gas burner comprises a mixing tube 1 and a jet or nozzle section 2. The mixing tube preferably comprises a longitudinal tube having an outwardly flared outer end 3 preferably formed on a 4-inch radius, said flared portion merging with the body of the tube at its point of narrowest diameter. From said point the tube increases in diameter at the rate of one degree per unit of length and terminates in a substantially horizontal aperture equal to the maximum width of said tube. Said aperture is surrounded by a projecting flange 4 on the inner edge of the tube providing an annular shoulder 5 outwardly thereof. The base of the nozzle portion of the burner is provided with an aperture, of a size equal to that in the tube, about which a shoulder 6, and flange 7, complementary to those of the tube are formed. Said shoulders and flanges are adapted to interengage, and the apertures in the tube section and nozzle section of the burner are thus kept in register through all angular adjustments of the nozzle section. In standard installations the burner section is placed above the tube section as is shown in Fig. 1. The two parts are held in assembled relation by means of a bolt 11 passing centrally through the registering apertures of the two sections and through bolt holes 12, 13, formed in the upper plate of the burner section and in the base of the tube section, respectively. The tube section may be somewhat thickened at the point where the bolt penetrates the same and is provided with a flattened base 14, against which the adjusting nut bears. The nozzle section of the burner preferably is formed of a pair of plates of segmental outline, the lowermost plate 15 having a hollowed central portion of increasing depth toward its point of attachment to the tube, and the upper plate 16 being of substantially flat shape. The forward edge of each of said plates is provided with a series of marginal lugs or projections 17. These lugs preferably have substantially flat exterior faces 18 conforming, however, to the slight curvature of the outer edge of the nozzle section and rounded inner faces 19, as is shown more particularly in Fig. 5 of the drawing.

The lugs are each formed with an enlargement 21 stepped or offset from the main body portion on the inner side thereof. In addition to being rounded the inner faces of the

lugs are slightly inclined or beveled so as to provide end faces of reduced area. In the form of lug 22, shown in Fig. 7, each lug is solid, or undivided, but in the preferred form 5 of construction shown in Fig. 5 and Fig. 6 each lug is notched or is formed of two complementary halves 23, 24, which are placed together so as to have a combined exterior outline similar to that of the solid lug shown 10 in Fig. 7. Thus a space is provided centrally of each lug radial to the arc-shaped outer edge of the nozzle member. When the plates are engaged with each other their meeting 15 edges are sealed about the sides and back with any suitable solder or cement, and at their forward edges the oppositely positioned projecting elements provide a passageway 20 for the gases of combustion. The side edges are preferably flanged.

20 In addition to the method of securing the marginal edges of the two sections of the nozzle portion of the device together, it has been found desirable to place at an approximately central position a securing bolt 31 through 25 apertures 32, 33, formed through said plates, strengthening ribs 34 and bosses 35 also being provided adjacent said apertures.

The hollowed portion of the nozzle, as stated, preferably becomes slightly less in 30 height and greater in width in a direction from the point of pivotal support to the apertured nozzle. The irregular outline of the 35 passageway through which the fuel gases emerge is of much importance. Said passageway is continuous from end to end across the arc-shaped front edge of the nozzle and presents a sinuous outline, the top and bottom portions of which present an area for the passage of gas, considerably larger than 40 the side portions thereof. This passageway, as viewed from the front of the nozzle, shows a series of steps and inclined side faces and the ends of each of the projecting lugs are blunt straight edges parallel to the bases 45 thereof.

At the rearward end of the gas mixture tube a cross-support 41 is provided, said support preferably having a central enlargement 42 of cylindrical shape to receive the 50 gas jet or gas supply nozzle. A set-screw 43 engaged within said cylindrical enlargement provides a means of clamping said gas supply nozzle in adjusted position.

Other modes of applying the principle of 55 my invention may be employed instead of the one explained, change being made as regards the structure herein disclosed, provided the means stated by any of the following claims or the equivalent of such stated means be 60 employed.

I therefore particularly point out and distinctly claim as my invention:—

1. A burner for gas stoves, comprising a gas mixing section, an elongated nozzle section having peripheral orifices at its forward end, said mixing section being provided with a horizontally positioned aperture and said nozzle section being provided at its rearward end adjacent its under side with a similar aperture, circular bearing surfaces adjacent 65 said apertures for adapting the parts to have movement relative to each other to provide flame positioning adjustment, a bolt positioned centrally of said apertures and bearing against the outer face of said mixing and 70 nozzle sections for securing the same against movement, and a series of spaced lugs at the forward end of said nozzle section producing a continuous passageway for the fuel 75 gases.

2. A burner for gas stoves, comprising a gas mixing section, an elongated nozzle section having peripheral orifices at its forward end, said mixing section being provided with a horizontally positioned aperture and said 85 nozzle section being provided at its rearward end adjacent its under side with a similar aperture, circular bearing surfaces adjacent 90 said apertures for adapting the parts to have movement relative to each other, a bolt positioned centrally of said apertures and bearing against the outer face of said mixing and nozzle sections for securing the same against 95 movement, and a series of spaced lugs formed on the upper and lower portions of the nozzle 95 section of the burner and spaced to form a sinuous passageway for the gases passing through said burner.

3. A burner for gas stoves, comprising a gas mixing section, an elongated nozzle section having peripheral orifices at its forward end, said mixing section being provided with a horizontally positioned aperture and said nozzle section being provided at its rearward end adjacent its under side with a similar 100 aperture, circular bearing surfaces adjacent 105 said apertures for adapting the parts to have movement relative to each other, a bolt positioned centrally of said apertures and bearing against the outer face of said mixing and 110 nozzle sections for securing the same against movement, and a series of lugs having inclined sides and off-set sections 115 immediately thereof formed on the upper and lower portions of the nozzle section of the burner and spaced to form a sinuous passageway throughout its length for the gases passing through said burner.

Signed by me, this 16th day of June, 1924.
BERNARD A. GEURINK.
